UNITED STATES PATENT OFFICE.

JOHN D. COLE, OF PHELPS, NEW YORK.

DEVICE FOR ADJUSTING AND HANGING CARRIAGE-BODIES.

Specification forming part of Letters Patent No. **88,944**, dated April 13, 1869.

To all whom it may concern:

Be it known that I, JOHN D. COLE, of Phelps, in the county of Ontario and State of New York, do hereby declare that the following is a description of my Improvement for Hanging Carriage-Bodies, reference being had to the drawings herewith annexed, of which—

Figure 1 is a side view, showing the machine in operation. Fig. 2 is a perspective view of the machine or instrument itself.

A A A A are bars or slats, which can be adjusted, by means of the thumb-screws F F and the rectangular boxes G G, to fit buggies of different lengths. B B B B are metallic hooks attached to the slats. C C C C are screws, which pass through the slats, having a crank at the lower end. D is a slotted bar, which connects the slats, and is lengthened or shortened by means of the thumb-nuts E E.

The operation of the instrument is this:

Suppose the gearing of a carriage to be ironed and ready for the hanging of the body. Attach the instrument to the spring-bars by means of the hooks B B B B, as shown in Fig. 1, place the body upon the instrument, and adjust to the proper position by the screws C C C C. The body-loops may now be fitted accurately without the inconvenience of boxes, blocks, &c., which is experienced in leveling up and hanging bodies in the usual manner.

What I claim as my invention, and desire to secure by Letters Patent, is—

The instrument for hanging carriage-bodies, constructed and operating substantially as herein specified.

JOHN D. COLE.
